CLAIM

The ornamental design for a toddler's drinking cup lid, as shown and described.

DESCRIPTION

FIG. 1 is a top plan view of a toddler's drinking cup lid showing my new design;

FIG. 2 is a bottom plan view;

FIG. 3 is a front elevation view;

FIG. 4 is a rear elevation view;

FIG. 5 is a left side elevation view;

FIG. 6 is a right side elevation view;

FIG. 7 is a top perspective view;

FIG. 8 is a bottom perspective view;

FIG. 9 is a left side elevation view showing the design in an environment of use; and,

FIG. 10 is a second top perspective view, showing the device in an environment of use.

The broken lines showing the cup and straw in FIGS. 9 and 10 show the environment in which a toddler's drinking cup lid is used and forms no part of the claimed design.
